Inventor:

Frances Nash

UNITED STATES PATENT OFFICE.

FRANCES NASH, OF NEW YORK, N. Y.

WOMAN'S GARMENT.

1,232,068.

Specification of Letters Patent.

Patented July 3, 1917.

Application filed July 24, 1916. Serial No. 110,890.

To all whom it may concern:

Be it known that I, FRANCES NASH, a citizen of the United States, and a resident of New York city, in the county and State 5 of New York, have invented certain new and useful Improvements in Women's Garments, of which the following is a specification, reference being had to the accompanying drawings and made a part of this speci- 10 fication.

My invention relates to a simplified garment for women's apparel, the advantages of which will hereinafter be stated.

Primarily, my invention resides in a single 15 undergarment, designed to replace the chemise or vest, drawers, corset and corset cover, and will be found convenient for general wear. It will be particularly useful in athletics, as well as for dancing, bathing 20 or theatricals. The garment is so constructed as to be easily placed in position on the body of the wearer, and will require no covering other than the usual outer garments. It will be particularly serviceable 25 for wear in warm climates, and will reduce materially the weight of the clothing heretofore necessary. The garment is a unit composed of a chemise, corset and knickerbockers.

I have provided also a construction which 30 will permit the ready removal of the boning strips for the purpose of laundering the garment.

In the accompanying drawings,

Figure 1 is a front view of the garment as it is intended to be worn,

Fig. 2 is a view of the garment opened so as to show the interior features of the construction,

Fig. 3 is an illustration, in detail, of the 40 arrangement of the casings for the boning strips, so as to permit the ready removal of the latter,

Fig. 4 is a detailed view showing the 45 manner in which the corset steels are held in place, and,

Fig. 5 is an open view, showing the construction whereby the corset steels are held in place.

A is the bust portion, B the body portion, 50 and C the knickers, or drawers. The garment comprising these three features is made as an integral structure, of any materials suitable for the particular use, or lo- 55 cality, where it may be worn. The bust portion A may be ornamented in any pat-

tern desired, so as to present a good appearance when worn with a sheer waist. The body portion B, which takes the place of the corset, will be suitably boned so as to 60 give the desired close fit about the waist and hips. The knickers C will be contracted at their lower parts by an elastic band, which may be run through a casing formed in a hem. 65

In practice, I have found it best to form the garment of four gores, seamed down the middle of the back and under the arms. Darts will be inserted in the body portion to provide the necessary fullness about the 70 hips.

To the inside of the body portion, I provide a suitable number of casings 3, for the boning strips 2. These casings are formed by attaching to the body, strips of 75 reinforcing material 30 of the length of the boning. Upon these reinforcing strips, I superpose pieces of tape, which are attached to the reinforcing strips so as to form pockets for the boning strips. A blank space is 80 provided between the adjacent ends of the tape on each reinforcing strip, so as to permit the ready insertion of the boning strips, and their withdrawal by springing, when it is desired to laundry the garment. The 85 reinforcing strip is formed of some durable material so as to resist the tendency of the boning strips to wear through the garment.

It will be observed that the casings, while extending above and below the waist line, 90 terminate short of both the top and bottom of the garment.

The meeting edges of the body portion of the strips are provided with eyelets 4 and 6 and slotted openings 5, through the latter 95 of which will be projected the hooks 1' of the corset steels 1. After the corset steel is in place, a lace 8 will be run through the eyelets 4 and 6 to hold the steel in position. A similar arrangement is provided at 100 the other side of the garment for the corset steel, carrying the usual pins provided for engaging the hooks 1', when the garment is placed in position on the body of the wearer. 105

When in position, the knickers are closed by glove fasteners or snap catches 9. Similar fastening devices 10, or buttons will be provided for the meeting edges of the bust portion.

I have also provided a means for attaching a flounce D to the knickers, if desired,

using for this purpose the usual glove fasteners or snap catches. These flounces may be of any length or shape desired.

5 Hose supporters are arranged inside of the knickers.

By the use of my invention, with the provision for ready removal of the boning strips, a serious objection existing in garments now in the market is overcome, in 10 that the garment may readily be laundered without the damage which heretofore has been inseparable in similar garments in which the boning is permanently attached.

While I have shown my garment in the 15 form in which I prefer to make it, it will be understood that the details of construction may be somewhat changed, when found necessary, without departing from the spirit of my invention.

20 What I claim, and desire to secure by Letters Patent is:

1. A one piece women's garment, comprising a bust portion, a boned body portion for confining the waist and hips, and knickers, the inside of the body portion being

provided with casings for the reception of the boning strips, such casings being closed at their ends and provided with a central opening for the insertion and removal of the boning strips, for the purpose of laundering the garment, said casings extending above and below the waist line and terminating short of both the top and bottom of the garment. 30

2. A one piece women's garment, comprising a bust portion, a boned body portion for confining the waist and hips, and knickers, the inside of the body portion being provided with casings for the reception of the boning strips, such casings having openings 35 for the ready insertion and removal of the boning strips, for the purpose of laundering the garment, said casings extending above and below the waist line and terminating short of both the top and bottom of 40 the garment.

In testimony whereof, I have signed my name this 22nd day of July, 1916.

FRANCES NASH.
